UNITED STATES PATENT OFFICE.

FRIEDRICH AUGUST HERMANN FAULHABER AND CHRISTOPH FRIEDRICH KOCH, OF SCHWÄBISCH HALL, GERMANY.

HINGE.

SPECIFICATION forming part of Letters Patent No. 487,476, dated December 6, 1892.

Application filed December 31, 1890. Renewed May 21, 1892. Serial No. 433,792. (No model.)

To all whom it may concern:

Be it known that we, FRIEDRICH AUGUST HERMANN FAULHABER and CHRISTOPH FRIEDRICH KOCH, subjects of the King of 5 Würtemberg, German Empire, and residents of the city of Schwäbisch Hall, in the Kingdom of Würtemberg, German Empire, have invented certain new and useful Improvements in Door-Hinges, of which the following 10 is a specification.

This invention relates to door-hinges, and especially to pivot-hinges for doors that open in both directions. With the pivot-hinges in use heretofore considerable difficulty was experienced in removing or replacing the door 15 without mutilating or defacing the frame in which the door was hung or the door itself.

The object of our invention is to provide a new and improved pivot-hinge, which is so 20 constructed that the door can readily be hung or removed.

The invention consists in the construction and combination of parts and details, as will be fully set forth hereinafter, and pointed out 25 in the claim.

In the accompanying drawings, Figure 1 is an elevation of a door provided with our improved pivot-hinges adapted to slide on the door from the rear edge, parts being broken 30 out and others being in section. Fig. 2 is an elevation of a door provided with our improved pivot-hinges adapted to be placed laterally on the door, parts being broken out and others being in section. Fig. 3 is a vertical longitudinal sectional view, on an enlarged scale, of our improved construction of 35 pivot-hinges shown in Fig. 1. Fig. 4 is a plan view of the same. Fig. 5 is an end view, parts being in section. Fig. 6 is an enlarged face view of the pivot-hinge shown in Fig. 2, parts being in section. Fig. 7 is a plan view of the same. Fig. 8 is a vertical longitudinal sectional view. Fig. 9 is an elevation of a door provided with a construction of our improved 40 pivot-hinge wherein the pivot is fastened to the door-casing. Fig. 10 is an enlarged longitudinal sectional view of our improved pivot-hinge shown in Fig. 9. Fig. 11 is a vertical transverse sectional view of the bottom 45 plate, and Fig. 12 is a view of the under side of the upper plate.

Similar letters of reference indicate corresponding parts.

The pivot C, adapted to turn in the socket C', projects from the horizontal dovetailed arm of an angle-iron B. The angle-iron A, placed in a suitable recess at the corner of the door T, is provided in its horizontal arm with a dovetail recess, as shown in dotted lines in Fig. 4, adapted to receive the dovetail horizontal arm of the angle-iron B. Said horizontal arm is slid in said dovetail recess, the vertical arm of the angle-iron B passing into vertical recesses in the outer surface of the vertical arm of the angle-iron A. By means 65 of screws b the angle-iron B is held in place in the recesses of the angle-iron A, and screws a serve to hold the angle-iron A on the corner of the door. To remove the door, the screws b are loosened, when the door can be 70 pulled out in the direction of the length of the horizontal arm of the angle-irons A and B. The sockets C' are fastened in suitable recesses in the top and bottom cross-pieces 75 of the door-frame, as shown in Fig. 1.

In the construction shown in Figs. 2, 6, 7, and 8 the angle-iron A is fastened in a recess in the side or face of the door, and the angle-iron B slides laterally into the same, the angle-iron A' being fastened by the screws a' 80 and the angle-iron B' being fastened by the screws b'. To remove the door, the screws b' are loosened and the door at the hinged end is moved outward laterally, so as to withdraw the angle-iron A' from the angle-iron B', carrying 85 the pivot C, that rotates in the socket C'.

In the construction shown in Figs. 9 to 12 the pivot is not held on the door, but on the casing. Said pivot C projects downwardly from the wedge-shaped dovetailed plate B², 90 placed into a wedge-shaped dovetailed recess A³ in the under side of the plate A², which is fastened by screws a² in the bottom surface of the top cross-piece of the door-casing or in the upper surface of the bottom cross-piece. 95 The recess A³ is longer than the sliding piece B², so as to adapt said piece to slide in said recesses. The plate D² is fastened by means of screws d² on the top or bottom edge of the door and is provided at one end with the aperture through which the pivot C can pass. 100 A screw b² serves for holding the sliding

piece B² in place in the guide or groove A³ of the plate A².

To remove the door, the same is first opened, so as to give access to the screw b², which is loosened, and then the door is removed in such a direction as to cause the wedge-shaped dovetailed piece B² to slide lengthwise, as indicated by the arrow in Fig. 12 in the groove A³. As the said wedge-shaped dovetail

piece B² is now in the wider end of the groove A³ it can easily be moved out of said groove, thus permitting the detaching of the door.

Having thus described our invention, we claim as new and desire to secure by Letters

15 Patent—

The combination, in a door-hinge, of an an-

gle-iron adapted to be fastened on the door and provided with a dovetail groove, an angle-iron provided with a dovetail part adapted to slide in the dovetail groove of the angle-iron on the door, a pivot on said sliding angle-iron, screws for fastening an angle-iron on the door, and screws for fastening the angle-iron bearing the pivot to the angle-iron on the door, substantially as set forth. 25

In witness whereof we have hereunto set our hands in presence of two witnesses.

FRIEDRICH AUGUST HERMANN FAULHABER,
CHRISTOPH FRIEDRICH KOCH.
